UNITED STATES PATENT OFFICE.

GEORGE DRUMMOND, OF PHILADELPHIA, PENNSYLVANIA.

CHART FOR DRAFTING PATTERNS FOR GARMENTS.

SPECIFICATION forming part of Letters Patent No. 451,553, dated May 5, 1891.

Application filed August 9, 1889. Serial No. 320,820. (No model.)

To all whom it may concern:

Be it known that I, GEORGE DRUMMOND, of the city of Philadelphia and State of Pennsylvania, have invented a certain new and 5 useful Improvement in Charts for Garment-Fitting; and I do hereby declare the following to be a full, clear, and exact description thereof, reference being had to the accompanying drawings or charts, forming part of 10 this specification.

My invention has relation to charts for drafting ladies' basques, waists, and other close-fitting garments; and it consists in charts 15 scaled and constructed as hereinafter particularly described, and claimed.

The respective measurements having been taken and registered onto the pattern-sheet, the chart is removed, and the points indicated on the pattern-sheet are then connected and the 20 proper form-lines drawn by the aid and means of a suitable drafting-instrument.

In drafting patterns for a dress-body I employ five charts and any suitable drafting-instrument—a front chart, which represents 25 one-half of the front of the body; an under-arm chart, which represents the piece immediately under the arm forming up to the front; a side-body chart, which represents the side piece formed up to the under-arm piece; a 30 back chart, which represents one-half of the back joined onto the side piece; and the sleeve chart, which represents the upper and under side of the sleeve.

I will now describe my invention, so that 35 others skilled in the art to which it appertains may make and use the same, reference being had to the accompanying drawings, forming part of this specification.

Figure 1 represents the front chart. Fig. 40 2 represents the under-arm chart. Fig. 3 represents the side-body chart. Fig. 4 represents the back chart. Fig. 5 represents the sleeve chart.

The charts are graded and scaled by a series 45 of cross-numbers and cross-lines, particularly at the points where the several indicating dots or points are to be laid off. Any even gradation or scale may be employed. The series shown on the drawings of the charts 50 are preferable. The charts are of a size corresponding to the measurements taken from the body and to the actual size of the pattern.

In the accompanying drawings, as a matter of reference and convenience, a pattern-line is drafted in heavy lines to a particular-sized 55 form, which may be followed as a reference and illustration. The checker-board charts are cross-numbered, as shown in the drawings, and are preferably perforated at each point of juncture of the lengthwise and latitudinal lines as a matter of convenience. The charts represent the full length and depth of the pattern to be drafted. The paper upon which the pattern is to be drafted is secured underneath the chart, and as each measurement is taken the point of a pencil is inserted 60 into the perforations in the chart at the proper point indicated by the cross-numbers, according to the measurement taken and the point indicated on the pattern-paper below. All the 65 points being thus laid onto the pattern-paper they are joined and given the proper lines and curves by means of any suitable drafting-instrument.

Referring to Fig. 1, front chart, point or dot 75 No. 11 represents the neck in front, as indicated by the neck-measure line No. 11 for ordinary forms. Line No. 11^A is for slightly stooping forms, and line No. 11^B for full-stooping forms. Point or dot No. 12 represents the 80 neck or shoulder line, as indicated by neck measure. Line No. 1 is for ordinary forms. Line No. 2 is for slightly-stooping forms, and line No. 3 is for full-stooping forms. Point or dot No. 13 represents the length of shoulder from point No. 12, line No. 1. Point or dot No. 14 represents the inner portion of the arm's eye to point indicated by the chest-depth and chest-line measures. When 11^A is used, extend the point one-fourth of an inch 90 to the front. When 11^B is used, extend it one-half an inch to the front. Point or dot No. 15 represents the arm's eye immediately under the arm, as indicated by the chest-depth and bust-line measures. When No. 2 95 line at point 12 is used, raise this one-fourth of an inch. When No. 3 line is used, raise it one-half of an inch. Point or dot No. 21 represents the bust-line in front, as indicated by the bust-depth measure at dark line for ordinary forms. Should the bust-line measure be one inch in excess of the chest-line measure, it will be one-fourth of an inch to the front of dark line, and the bust measure will be re- 100

duced one-half of an inch at all other points of the bust-line. If two inches in excess of the chest-line measure, it will be one-half of an inch to the front of the dark line, and the bust measure will be reduced one inch at all other points of the bust-line. If three inches in excess of the chest-line measure, it will be three-fourths of an inch to the front of the dark line, and the bust measure will be reduced one and one-half inch at all other points of the bust-line. Point or dot No. 22 represents the front depth from the center of the neck at back over the shoulder to waist-line in front, also the depth for the neck in front to waist-line in front, as indicated by the respective measures by following the neck-measure column of front-depth table. Point or dot No. 23 represents the hip depth in front five inches below the waist-line. Point or dot No. 24 represents the waist-line under the arm, as indicated by the waist depth to point in a line with the bust measure. When points 12 and 15 are raised for stooping forms, raise this to correspond. The darts are given in table by following the bust-measure columns to point showing the waist measure, and square to the left hand the allowance for each dart is shown. Point or dot No. 26 represents the hip-line at side in a line with the hip depth to point opposite the bust or waist measures. Point or dot A represents the front line of front dart at waist-line. Point or dot B represents the back line of front dart at waist-line. Point or dot C represents the top of front dart, as indicated by bust depth and bust measure. Point or dot D represents the depth of front dart one-fourth of an inch to the right hand of A. Point or dot E represents the front line of back dart at waist-line. Point or dot F represents the back line of back dart at waist-line. Point or dot G represents the top of back dart, as indicated by bust depth and bust measure. Point or dot H represents the depth of back dart one-half of an inch to the right hand of E.

Referring to Fig. 2, under-arm chart, point or dot No. 16 represents the front part of the arm's eye, as indicated by the chest depth. Point or dot No. 17 represents the upper part of the arm's eye, as indicated by the chest depth and bust measure. Point or dot No. 25 represents the waist-line in front, as indicated by the waist depth. Point or dot No. 28 represents the waist-line at back, as indicated by the waist depth to point opposite the waist-line measure. Point or dot No. 27 represents the hip depth in front. Point or dot No. 30 represents the hip depth at back to point indicated by waist or hip measures.

Referring to Fig. 3, side-body chart, point or dot No. 18 represents the front part of the arm's eye, as indicated by chest depth and bust measures. Point or dot No. 19 represents the upper part of the arm's eye, as indicated by chest depth and bust measures. Point or dot No. 29 represents the waist-line

in front to point indicated by the back depth and waist measures. Point or dot No. 32 represents the waist-line at back to point indicated by the back depth and waist measures. Point or dot No. 31 represents the hip depth in front to point indicated by the waist or hip measures. Point or dot No. 34 represents the hip depth at back to point indicated by the waist measure.

Referring to Fig. 4, back chart, point or dot No. 36 represents the center of neck at back for ordinary forms. No. 36^A is for medium-stout forms, and No. 36^B is for stout forms. When No. 36^A or 36^B is used, the back depth at point No. 40 must be lowered to correspond. Point or dot No. 37 represents the neck at shoulder-line, as indicated by neck measure. Line 37^A is for stout forms. Point or dot No. 38 represents the length of shoulder from point 37 by following the line from the neck measure until in a line with the bust measure. Point or dot No. 20 represents the lower portion of the arm's eye, as indicated by chest depth and bust measures. Point or dot No. 39 represents the chest depth at center of back. Point or dot No. 33 represents the waist-line in front, as indicated by back depth and point opposite the waist measure. Point or dot No. 40 represents the waist-line at center of the back, as indicated by the back depth. When this point is lowered, the waist-line must slope from the under arm. Point or dot No. 35 represents the hip depth at side to point indicated by waist or hip measures. Point or dot No. 41 represents the hip depth at center of the back.

Referring to Fig. 5, sleeve chart, point or dot No. 1 represents the upper part of the arm's eye resting on the shoulder, as indicated by the arm's-eye measure. Line No. 1 gives the exact size of the arm's eye. No. 1^{SG} allows one inch extra for fullness. No. 1^G allows two inches extra for fullness. Point or dot No. 2 represents the front part of the arm's eye of upper and under portions, as indicated by the arm's-eye measure. Point or dot 3 represents the back part of the arm's eye of upper portion, as indicated by the arm's-eye measure. Point or dot No. 4 represents the back part of the arm's eye of under portion, as indicated by the arm's-eye measure. Point or dot 5 represents the inner or under side of upper portion at elbow-line, as indicated by length to elbow. Point or dot 5^A represents the inner or under side of under portion at elbow-line, as indicated by length to elbow. Point or dot No. 6 represents the elbow-line of under portion, as indicated by elbow measure. Point or dot No. 7 represents the elbow-line of upper portion, as indicated by elbow measure. Point or dot No. 8 represents the under side of upper portion at wrist-line, as indicated by sleeve length. Point or dot No. 8^A represents the under side of under portion at wrist-line, as indicated by sleeve length. Point or dot No. 9 represents the outside of under portion at

wrist-line, as indicated by sleeve-length and hand measures. Point or dot No. 10 represents the outside of upper portion at wrist-line, as indicated by sleeve-length and hand 5 measures.

As herein described, the charts are preferably perforated at the point of juncture of the latitudinal and longitudinal lines for the purpose of conveniently transferring to the 10 pattern - sheet beneath the measurements taken by introducing the point of the pencil; but I do not limit myself to this means for transferring the measurements to be indicated by means of the chart onto the pattern- 15 sheet, as it might be done by interposing a carbon-sheet between the pattern and the chart or in other ways.

Having thus described my invention, what I claim, and desire to secure by Letters Patent, is—

1. A chart for drafting garments, having a number of independent scales consisting of two numbered series of parallel lines, one series intersecting the other series, the scales 25 being located in positions approximating the positions of the several points of measurement, and the points of intersection of the several lines designating the exact positions of the several points of measurement on any 30 form, the chart being further provided at its front edge with a heavy line parallel with said edge to designate the bust-line in ordinary forms and with parallel lines to meet the measurements of irregular forms, and being 35 further provided at its upper end with a series of parallel lines for the neck measure, one of said lines being heavy to designate ordinary forms, as specified.

2. A chart for drafting garments, having a 40 number of independent scales consisting of two numbered series of parallel lines, the one series intersecting the other series, the scales being located in positions approximating the

positions of the several points of measurement and the points of intersection of the 45 several lines designating the exact positions of the several points of measurement of any form, the chart being further provided in its front section with a heavy line in front or on the left-hand side to designate the bust-line 50 for ordinary forms, with extra lines in front or on the left-hand side of the heavy line providing for cases of an excessive development of the bust in front and scaled for reducing the bust measure at other points corresponding to the increase applied to the bust in front, provided, also, with neck-scales for ordinary forms and extra parallel lines for stooping forms, and also provided with dart-scales giving the sizes of the respective darts to 60 meet the variations of the bust and waist measurements, providing for a larger dart in front when the waist-line is small in proportion to the bust-line, and vice versa, provided, further, with front-depth scale giving the 65 respective front-depth measures and designating the waist-line in front, and further provided with scales for adjusting the arm's eye, as specified.

3. A chart for drafting sleeves, provided 70 with dots 1, 1^G, and 1^{SG} at upper end, the dot 2 near the front edge, the dots 3 and 4 in rear of the dot 2, indicating the arm's eye, the dots 5, 5^A, 6, and 7, indicating the elbow-line, and dots 8, 8^A, 9, and 10 at lowest point, indicating the wrist-line and having a series of numbered lengthwise and latitudinal lines designating the position of said dots, substantially as described.

In witness whereof I have hereunto set my 80 hand this 8th day of August, A. D. 1889.

GEORGE DRUMMOND.
